UNITED STATES PATENT OFFICE

2,616,173

VERTICAL FEED BUTTER DISPENSER

Ronald R. Perkins, Dallas, Tex.

Application March 20, 1950, Serial No. 150,694

7 Claims. (Cl. 31—21)

1

This invention relates to a device for dispensing slabs or patties of butter.

An object of this invention is to provide a dispensing machine which includes a refrigerated housing adapted to keep butter solid, and electrically operated means for cutting slabs or patties of butter.

Another object of this invention is to provide a rotatable holder for sticks of butter, a stationary cutter, and an electric operator for progressively rotating the holder.

A further object of this invention is to provide in a dispenser of this kind, an improved holder for the sticks of butter and a spider follower for urging the sticks downwardly.

A further object of this invention is to provide an improved cutter for cutting slabs or patties from the butter sticks.

A further object of this invention is to provide a butter dispensing machine which is of simple construction which can be mounted on a counter or other convenient location.

With the above and other objects in view, my invention consists in the arrangement, combination and details of construction disclosed in the drawings and specification, and then more particularly pointed out in the appended claims.

In the drawings:

Figure 1 is a detailed front elevation of a butter dispensing device constructed according to an embodiment of this invention;

Figure 2 is an end elevation partly in section of the device;

Figure 3 is an enlarged fragmentary sectional view taken on the line 3—3 of Figure 2;

Figure 4 is an enlarged fragmentary sectional view taken on the line 4—4 of Figure 3;

Figure 5 is a horizontal section similar to Figure 4 with the butter carrier removed;

Figure 6 is a fragmentary sectional view taken on the line 6—6 of Figure 5;

Figure 7 is a diagrammatic view showing the spiral cutter;

Figure 8 is an enlarged fragmentary sectional view taken on the line 8—8 of Figure 5;

Figure 9 is the bottom plan view of the butter carrier;

Figure 10 is a fragmentary sectional view on an enlarged scale showing the securing of the receptacle in the refrigerated housing;

Figure 11 is an enlarged fragmentary sectional view taken on the line 11—11 of Figure 1;

Figure 12 is a diagrammatic view showing the electric circuit embodied in this invention;

Figure 13 is a fragmentary section view taken on the line 13—13 of Figure 11.

2

Referring to the drawings, the numeral 15 designates generally a housing, and the numeral 16 designates a lower housing secured to the housing 15 and enclosing a refrigerating unit 17. The refrigerating unit 17 is of conventional construction being an electrically operated cooling unit which has cooling coils 18 extending from the lower housing 16 upwardly into the interior of the upper housing 15. The housing 15 includes an inner cylindrical member 19 which is formed with an enlarged cylindrical upper portion 20 and defining a shoulder 21.

A receptacle generally designated as 22 is adapted to be removably mounted in the well or 15 cylindrical members 19 and 20 and includes a flared rim 23 having one or more locking pins 24 as shown in Figure 10 which are engageable in openings 25 formed in the shoulder 21. The pins 24 provide a means whereby the receptacle 22 will be held against rotation in the well 19. The well 19 includes a bottom wall 26 which is disposed above a shelf 27.

The bottom wall 28 of the receptacle 22 is formed with a spirally disposed cutting member 29 which is struck from the bottom 28 and forms an opening 30 through which the cut butter slices are adapted to pass.

The bottom wall 26 of the well 19 is formed with an opening 31 adjacent the cutter 29 so that 30 the butter slices will drop downwardly onto a receptacle or receiver which is positioned on the shelf or support 27.

A butter holder or carrier 32 is rotatably disposed in the receptacle 22 and includes a cylindrical inner wall 33 and a plurality of inwardly tapering lugs 34 which form spaces 35 between each pair of lugs within which a stick 36 of butter is adapted to loosely engage. A bottom plate 37 is secured to the cylindrical wall 33 and has projecting centrally and downwardly therefrom a shaft 38 formed with a polygonal stud 39 at its lower end. The cylindrical wall 33 is provided with vertically disposed slots 40 communicating the interior of the cylindrical member 33 with each space or chamber 35.

A follower generally designated as 41 is slidably mounted within the holder 32 and includes a plurality of weights 42 which are loosely engageable in the spaces 35 and are adapted to bear against the upper ends of the butter sticks 36. The several weights are connected together by radially disposed arms 43 which project from a central hub 44. The arms 43 loosely engage through the slots 40 of the cylindrical member 33.

In order to provide a means whereby the carrier or holder 32 may be progressively rotated so

that the lower end of each butter stick 36 will be brought into contact with the cutting blade 29, I have provided a ratchet lever 45 which is rotatable about the polygonal end 39 of the shaft 38. The ratchet lever 45 includes a lever arm 46 having secured thereto an annular housing 47, and a ratchet or toothed wheel 48 is fixed to the stud 39 and engages within the housing 47. A spring pressed pawl 49 having a spring 49a is carried by the housing 47 and engages the ratchet wheel 48 so as to provide for one way rotation of shaft 38. The ratchet lever 45 is adapted to be progressively rocked horizontally by means of a solenoid 51 disposed within the lower housing 16. The core 52 of the solenoid 51 is connected to the ratchet lever 45 by means of a connecting rod 53 extending loosely through an opening 54 formed in the end wall 55 of the lower housing 16. The solenoid 51 is connected to a source of electric current supply by means of conductors 56 and 57, and a spring pressed switch 58 is interposed in conductor 57.

Switch 58 is normally biased to a circuit breaking position and is disposed on the shelf 27 so that when a receptacle or receiver is disposed below the discharge opening 31, switch 58 will be closed, thereby energizing solenoid 51 and effecting the partial rotation of holder or carrier 32.

In the use and operation of this device the butter sticks 26 are inserted in the spaces or chambers 35 of the carrier or holder 32 after which the follower 41 is placed on top of the butter sticks as shown in Figure 3. When a receptacle is placed on top of the switch 58 solenoid 51 will be energized, thereby rotating holder or carrier 32 for one segment. Rotation of holder or carrier 32 will bring the lowermost stick on the spiral cutter into engagement with the cutting blade so that a butter slice will be cut from the stick 36, and this slice will be discharged through the opening 31 in the bottom wall 36. If desired, the switch 58 may be closed by pressing a finger thereagainst and supporting the receptacle below the delivery opening 32. A single butter slice will be delivered each time the solenoid 51 is energized. The cooling unit 17 is a relatively small cooling unit which is designed for the purpose of keeping the butter solid when disposed in the upper cooling housing 15. The cooling unit 17 is conventional.

What is claimed is:

1. A butter dispenser comprising a refrigerated housing having a well with a delivery opening in the bottom of the well, a cylindrical receptacle disposed in said well and including a bottom formed with a spiral guide terminating in a cutter, a cylindrical butter stick carrier rotatably disposed in said receptacle, said carrier having circumferentially spaced apart slots within which the butter sticks are loosely engageable, a follower in said carrier having weight means in said slots for gravitatingly urging the butter sticks downwardly, and electrically operated means operably connected to said carrier for progressively rotating said carrier whereby a slice of butter will be cut from each stick for delivery through said opening.

2. A butter slice dispenser comprising a refrigerated housing having a well with a delivery opening in the bottom of the well, a receptacle in said well, means holding said receptacle against rotation in said well, said receptacle including a bottom wall formed with a spiral outer portion terminating at the high portion thereof

in a cutter disposed at one end of said delivery opening, a butter stick carrier rotatable in said receptacle, a stud projecting from one end of said carrier, a ratchet lever carried by said stud, and solenoid means connected to said lever for progressively rotating said carrier and thereby moving the butter sticks on said carrier against said cutter for cutting a slice from each stick.

3. A butter slice dispenser comprising a refrigerated housing having a well with a delivery opening in the bottom of the well, a receptacle in said well, means holding said receptacle against rotation in said well, said receptacle including a bottom wall formed with a spiral outer portion terminating at the high portion thereof in a cutter disposed at one end of said delivery opening, a butter stick carrier rotatable in said receptacle, a stud projecting from one end of said carrier, a ratchet lever carried by said stud, a horizontally disposed shelf disposed below said delivery opening, solenoid means connected to said lever for progressively rotating said carrier, and a switch connected to said solenoid.

4. A butter slice dispenser comprising a refrigerated housing having a well with a delivery opening in the bottom of the well, a receptacle in said well, means holding said receptacle against rotation in said well, said receptacle including a bottom wall formed with a spiral outer portion terminating at the high portion thereof in a cutter disposed at one end of said delivery opening, a butter stick carrier rotatable in said receptacle, a stud projecting from one end of said carrier, a ratchet lever carried by said stud, a horizontally disposed shelf disposed below said delivery opening, solenoid means connected to said lever for progressively rotating said carrier, and a switch connected to said solenoid, said switch being disposed on said shelf in a position to be closed by a receiver positioned on said shelf.

5. In a butter dispenser, a casing for enclosing a refrigerating unit, a housing mounted on the top of said casing and including a cylinder provided with an enlarged upper portion defining a shoulder, there being a plurality of spaced openings arranged in said shoulder, a receptacle arranged in said cylinder and including a flared rim, locking pins extending from said rim into said openings, horizontally disposed spaced parallel shelves extending outwardly from said casing, said receptacle including a bottom wall, a spiral cutting member extending upwardly from said bottom wall, there being openings in the bottom of said cylinder and receptacle for the egress therethrough of butter slices, a carrier rotatably arranged in said receptacle and provided with spaces for receiving a stick of butter therein, there being a plurality of spaced slots arranged in said carrier, a follower slidably mounted in said carrier and including a hub, arms extending radially outwardly from said hub and projecting through said slots, weights secured to the outer ends of said arms for engaging the tops of the butter sticks and means operably connected to said carrier for progressively rotating said carrier.

6. In a butter dispenser, a casing for enclosing a refrigerating unit, a housing mounted on the top of said casing and including a cylinder provided with an enlarged upper portion defining a shoulder, there being a plurality of spaced openings arranged in said shoulder, a receptacle arranged in said cylinder and including a flared rim, locking pins extending from said rim into said openings, horizontally dis-

posed spaced parallel shelves extending outwardly from said casing, said receptacle including a bottom wall, a spiral cutting member extending upwardly from said bottom wall, there being openings in the bottom of said cylinder and receptacle for the egress therethrough of butter slices, a carrier rotatably arranged in said receptacle and provided with spaces for receiving a stick of butter therein, there being a plurality of spaced slots arranged in said carrier, a follower slidably mounted in said carrier and including a hub, arms extending radially outwardly from said hub and projecting through said slots, weights secured to the outer ends of said arms for engaging the tops of the butter sticks and means for progressively rotating said carrier, said means comprising a shaft extending downwardly from said carrier, a ratchet lever rotatable about said shaft and including a lever arm, an annular housing secured to said lever arm, a toothed wheel arranged in said annular housing, a spring pressed pawl carried by said annular housing for engaging the toothed wheel, a solenoid connected to a source of electrical energy for rocking said ratchet lever, and a spring pressed switch mounted on one of said shelves and connected to said solenoid.

7. In a butter dispenser, a casing for enclosing a refrigerating unit, a housing mounted on the top of said casing and including a cylinder provided with an enlarged upper portion defining a shoulder, there being a plurality of spaced openings arranged in said shoulder, a receptacle

arranged in said cylinder and including a flared rim, locking pins extending from said rim into said openings, horizontally disposed spaced parallel shelves extending outwardly from said casing, said cylinder including a bottom wall, a carrier rotatably arranged in said receptacle and provided with spaces for receiving a stick of butter therein, there being a plurality of spaced slots arranged in said carrier, a follower slidably mounted in said carrier including a hub, arms extending radially outwardly from said hub and projecting through said slots, weights secured to the outer ends of said arms for engaging the tops of the butter sticks, and means operably connected to said carrier for progressively rotating said carrier.
